UNITED STATES PATENT OFFICE.

FRANS BERT WENDEL, OF CRANFORD, NEW JERSEY, ASSIGNOR TO PATRICK SULLIVAN, OF NEW YORK, N. Y.

DESIGN FOR A TOY OR SIMILAR ARTICLE OF MANUFACTURE.

Application filed March 2, 1927. Serial No. 20,938. Term of patent 3½ years.

To all whom it may concern:

Be it known that I, FRANS BERT WENDEL, a citizen of the United States of America, residing at 103 Lincoln Avenue, Cranford, in the county of Union and State of New Jersey, have invented a new, original, and ornamental Design for a Toy or Similar Article of Manufacture, of which the following is a specification, reference being had to the accompanying drawing, forming a part thereof, and showing a perspective view of the toy embodying my design, comprising, mounted upon a suitable base, a grotesque cat figure in upright position chasing grotesque mice figures in upright positions and being followed by other grotesque cat figures in upright position.

I claim:

The ornamental design for a toy or similar article of manufacture substantially as shown and described.

FRANS BERT WENDEL.
